UNITED STATES PATENT OFFICE.

JOHNSON MILLS, OF PRESTWICH, COUNTY OF LANCASTER, ENGLAND.

STEAM-BOILER.

SPECIFICATION forming part of Letters Patent No. 423,792, dated March 18, 1890.

Application filed November 19, 1889. Serial No. 330,849. (No model.) Patented in England August 31, 1888, No. 12,545.

To all whom it may concern:

Be it known that I, JOHNSON MILLS, a subject of the Queen of Great Britain, and a resident of Prestwich, in the county of Lancaster, England, have invented certain new and useful Improvements in Steam-Boilers, (for which I have obtained a patent in Great Britain, No. 12,545, dated August 31, 1888,) of which the following is a full, clear, and exact specification.

This invention relates to the formation of parts of the shell, and also the end plates, of steam and water drums in water-tube steam-boilers.

15 The object of this invention is to construct said steam and water drums in such a manner that the pockets to which are connected these several nests of tubes of which water-tube steam-boilers are composed may be formed of part 20 or may otherwise constitute a part of the drum-shell and also of the end plates.

In order more clearly to describe this my invention, I have annexed hereunto two sheets 25 of drawings. In the several views therein shown similar letters refer to similar parts.

On Sheet 1 Figure 1 is a side view of front end of steam and water drum constructed according to this invention. Fig. 2 is a transverse section of same on line A A. Fig. 3 is 30 a view drawn transversely through the line C C, showing formation of drum-ring b in combination with pocket b'. Fig. 4 is a side view, and Fig. 5 a vertical section, on lines D D, of the combined drum-ring b and pocket b'. Fig. 6 is a sectional elevation of a modification. Fig. 7 is a side view of the rear end of steam and water drum. Fig. 8 is an end view 35 of the same. Fig. 9 is a transverse view of the combined end plate and pocket. Fig. 10 is a side view. Fig. 11 is a vertical section on the line F F of Fig. 9.

In constructing a steam and water drum according to this invention I form angular rings b and c in pairs, and either of mild steel 45 or other suitable material. I make these angular or flanged rings of the same diameter internally as the external diameter of steam and water drum a, in order that said rings may fit thereon and be riveted or otherwise 50 secured to steam and water drum, so as to form strengthening-rings at the joint of the

said drum. At the under side of rings b and c, I form pockets b' and c', either from plates which may be welded to said rings, and which may be dished out or pressed, or by other 55 suitable means constructed to the required shape. I rivet or otherwise join together the flanges b² and c², and by these means the combined rings b and c and pockets b' and c' form part of shell of steam and water drum a. I 60 attach to pocket b' the front headers of tubes e by means of ferrules or short connecting-tubes d, which may be placed either inclined or horizontally, as shown on drawings, and thus permit the nipples to be readily examined from the outside of front end of boiler.

I construct a pocket h', in combination with the end plate h at rear end of steam and water drum a by shaping and bending a plate of mild steel or other suitable material to the 70 required form and either riveting or welding the joints. The end plate h may either be dished or may be flat, as shown in drawings. I connect the back headers of tubes e to the pockets h' by means of short circulating 75 tubes or nipples f, which can be examined at the outside or rear end of boiler by removing the cap k opposite each tube. By these means increased strength in the upper steam and water drum a is obtained and additional 80 facilities for examination and repairs. The pockets b' and c', in combination with drum-rings b and c, and the pocket h', in combination with end plate h, may, when required, be formed at any other angle relatively with said 85 drums, rings b and c, and end plate h than as shown on drawings.

I deem it important that the pocket have a wall extending in line with the end plate, so as to have a firm bearing against the part 90 with which it comes in contact, and also that the remaining sides be inclined, so as to form a tapered pocket whereby it will be more firmly held in position and any tendency to settle will only hold the pocket more rigidly 95 in place.

No claim is made herein to the construction shown on Sheet 1 of the drawings—that is, a steam-drum provided with a depending pocket combined with independent headers 100 independently connected to the pocket by nipples—as the same forms the subject-matter of

my application, Serial No. 330,848, filed of even date herewith.

Having now particularly described and ascertained the nature of my said invention and 5 in what manner the same is to be formed, I declare that what I claim is—

In water-tube steam-boilers, an end plate h , shaped to form a pocket h' , with one side extended in line with the end plate and the

other sides inclined to give a tapered form to 10 the pocket, as set forth.

In testimony that I claim the foregoing I have hereunto set my hand this 1st day of November, 1889.

JOHNSON MILLS.
